Fig. 3

FIG. 1 is a partially exploded perspective view of a combined lighter and ashtrays showing my new design; combined lighter and ashtrays;

FIG. 2 is a side elevational view on a reduced scale of the combination lighter and ashtrays;

FIG. 3 is an exploded side elevational view thereof showing both ashtrays separated from the lighter base and the lighter striker separated from the lighter base; and

FIG. 4 is a perspective view of one of the ashtrays, the lighter and other ashtray being omitted for purposes of disclosure, it being understood that both ashtrays are identical.

I claim:

The ornamental design for a combination lighter and ashtrays, as shown and described.
